UNITED STATES PATENT OFFICE

JOHN VAN BRUNT, OF FLUSHING, NEW YORK, ASSIGNOR TO INTERNATIONAL COMBUSTION ENGINEERING CORPORATION, OF NEW YORK, N. Y., A CORPORATION OF DELAWARE

BOILER FURNACE

Application filed December 8, 1925. Serial No. 73,970.

This invention relates to boiler-furnaces, and is especially useful in connection with furnaces one or more of the boundaries of the combustion spaces of which is or are defined by water walls connected into the circulation of the boiler. The invention is also particularly applicable to pulverized fuel burning furnaces in which one or more of the upright sides of the combustion space are defined by boiler tubes subject to radiant heat.

The primary object of the invention is to ensure a proper circulation through such upright tubes or upright water walls.

The foregoing, together with such other objects as may hereinafter appear, or are incident to my invention, are realized by means of a construction which I have illustrated in the preferred form, in which—

Fig. 1 is a vertical section through a boiler furnace embodying my improvements.

Fig. 2 is a fragmentary vertical section taken on the line 2—2 of Fig. 1 drawn on an enlarged scale to more clearly illustrate details of the invention, and

Fig. 3 is a section taken on the line 3—3 of Fig. 2 looking in the direction of the arrows.

Referring now to Fig. 1, the reference character A denotes the combustion chamber having an outlet 7 in its upper part for the waste products of combustion, over which outlet is arranged the boiler elements 8. The pulverized coal is admitted into the combustion chamber through the arch 9 by means of a row of burners 10, the fuel descending 35 downwardly until the momentum of the fuel and flame stream is overcome, whereupon the fuel and flame stream ascends, the course taken by the fuel and flame stream thus describing a U. Preferably that portion of

the combustion chamber into which the fuel is admitted by the burners has its refractories exposed, whereby the entering fuel is subjected to radiant heat therefrom. The remaining portions of the upright walls of the combustion chamber are provided with the side water walls B, and the rear water wall C. The side water walls are composed of a plurality of upright tubes 11, each of which, on opposite sides, is provided with longitudinally extending fins 12, the fins and tubes

cooperating to form a substantially continuous metallic wall. The lower ends of the tubes 11 pass outwardly through the side walls of the combustion chamber for connection into the headers 13, and the upper ends of the tubes 11 pass out similarly for connection into the headers 14. The headers 13 are supplied with water by a downcomer means 15 and upcomer means 16 lead from headers 14 to the drum 17 of the boiler.

The rear water wall C is composed of similar tubes 11^a provided with similar fins 12^a. The upper ends of the tubes 11^a connect into the header 18 which has the upcomers 19 leading from opposite sides thereof to the drum 17. Each pair of the tubes 11^a have their lower ends connected into the junction blocks 20.

The lower portion of the combustion space immediately above the ash pit 21 is provided with a water screen composed of a plurality of spaced tubes 22, the rear ends of which are connected into the junction blocks 20. The front ends of the tubes 22 are connected into the header 23 which is supplied with water by the downcomer means 15.

Ordinarily no difficulty is encountered in connection with the circulation through the rear water wall. However, in installations of this character, difficulty in the circulation through the side water walls is encountered, particularly where the water is bad. It has been found that the circulation sometimes stops, and at other times is violently upwards, and at still other times is violently downwards.

To overcome this condition, I connect the headers 14 with the headers 13 by a plurality of tubes 24 located exteriorly of the setting. These tubes being located exteriorly, and, therefore, remote from the source of heat, ensure that the circulation through the upright water walls will always be in an upward direction. The importance of securing proper circulation through the tubes of the side water walls will be realized, when it is considered that such tubes are subjected to radiant heat coming opposite the zone of highest temperature. Such being the case, these tubes will burn out if the circulation there-

through is not rapid and continuous. By my improved arrangement I find that I overcome the difficulties and ensure proper circulation.

It will be noted that the spacing of the tubes 24 varies, the spacing being closest toward the lower ends of the headers 13 and 14 for the reason that that portion of the water wall served by these portions of the headers is opposite the zone of highest temperature.

10 The number, and therefore the total capacity, of the tubes 24 is less than that of the tubes 11 in the screen B. This arrangement will prevent an independent circulation of all of the water in the screen B, and will ensure that part of the water in the screen is always in the general boiler circulation.

What I claim is:—

15 In combination, a boiler, a combustion chamber, a plurality of upright tubes defining a portion of the combustion space, a header into which the upper ends of said tubes are connected, a header into which the lower ends of said tubes are connected, down-comer means connecting said lower header with the boiler, up-comer means connecting said upper header with the boiler, and other tubes outside the combustion chamber directly connecting said headers together, said 20 latter tubes being spaced more closely adjacent the region in which the first mentioned upright tubes are subjected to the greatest heat.

In testimony whereof I have hereunto
35 signed my name.

JOHN VAN BRUNT.
